UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

TOASTER-TRAY BUTTON.

Application filed April 6, 1923. Serial No. 630,272.

My invention relates to electric table cooking devices and particularly to electric toasters.

The object of my invention is to provide a relatively simple, inexpensive, easily manufactured, and easily assembled mechanism for operating the reversing trays of electric toasters.

In practicing my invention I provide a toaster frame comprising a base and side and top frames, in which a plurality of trays are mounted to have a turning movement relatively to the frame and to a heating element supported between the side frames in the base. The side portions of each of the trays are provided with openings through which one end of a tubular member may extend and be interlocked therewith. The other end of the tubular member is provided with a serrated edge that is adapted to engage, and interlock with a knob or button.

A machine bolt extends through the button, the tubular member and a spring washer that engages the outer flat surface of the button. The nut mounted on the inner end of the machine bolt is held in its proper operative position relatively to the bolt by projections integral with the side portions of the trays to prevent turning movement thereof relatively to the bolt.

In the single sheet of drawings,

Figure 1 is a partial view, in side elevation, of an electric toaster comprising the device embodying my invention,

Fig. 2 is a view, in vertical section, through a portion of a toaster illustrating more particularly the device embodying my invention,

Fig. 3 is a view, in end elevation, of a side portion of a tray comprising a part of an electric toaster,

Fig. 4 is a view, in side elevation, of a tubular member comprising a part of the device embodying my invention and,

Fig. 5 is a developed view of the member illustrated in Fig. 4.

An electric toaster 11 comprises a base 12, consisting of a stamped, sheet metal plate having a top portion and a plurality of integral depending flanges 13. Each of the flanges 13 is provided with integral end portions 14 extending angularly relatively to the flanges 13 and located in the same plane, and a plurality of supporting means 15 of a suitable heat-insulating material are

secured against the end portions adjacent the inner surface thereof. The construction of the base and of the end portion is more particularly disclosed and claimed in my co-pending application, Serial No. 630,271, filed April 6, 1923, and assigned to the W. E. & M. Co. (Case 10241), to which application reference may be had for further details of construction.

A plurality of vertically extending side frames 16 (a portion of which is illustrated in Fig. 2) are mounted on the top of the base 12 and are suitably secured thereto. A vertically extending heating element 17 comprises a plurality of sheets of insulating material, such as mica, upon which a resistor (not shown) is mounted.

A plurality of trays 18 having integral and laterally-extending side portions 19 are provided and are pivotally mounted in the side frames 16 in a manner to be hereinafter set forth in detail. Reference may be had to the hereinbefore mentioned application for further and more complete details of construction of these parts of the device which are not here illustrated nor described in detail as they form no part of my present invention.

Each of the side frames 16 is provided with openings 21 extending therethrough adjacent the outer edges thereof just above the bottom edge of the frames. Each of the side portions 19 of the trays 18 is provided with a substantially circular opening 22 therethrough. Portions 23 of the sides 19 are punched outwardly immediately adjacent the openings 22, the two portions 23 being located on a diametral line of each of the openings 22, whereby an opening is provided in each of the side portions 19 that is irregular in contour and comprises a substantially circular portion having two extensions.

A tubular member 24 comprises a punched piece of sheet-metal that is provided with a serrated outer edge 25 and two integral, longitudinally-extending lugs 26 that are so spaced as to be located on a diametral line when the sheet is rolled up to substantially tubular form, as illustrated more particularly in Fig. 4 of the drawing. The member 24 constitutes a tubular bearing-member and support for one end of a tray 18 and extends through, and has a loose fit in one of the openings 21 in the side frame 16. A

molded knob 27 of a suitable heat-insulating material and of any suitable or desired contour is located in close operative engagement with the serrated edge 25, with which 5 serrated edge the inner surface of the knob or button 27 is adapted to interlock.

A spring washer 28 is provided adjacent to the outer surface of the knob 27 and a machine bolt 29 extends through a suitable 10 opening in the knob 27 and through the tubular member 24, and is of such a length as to extend through the opening 22 and slightly 15 beyond. A hexagonal nut 31 has screw-threaded engagement with the inner end of the machine bolt 29 and the distance 20 between the integral inturned portions 23 is such as to permit the nut 31 to be located between the portions 23 and to fit substantially tightly to prevent a turning movement of the nut 31 relatively to the machine bolt 29.

The device embodying my invention provides a tubular bearing member of relatively 25 large external diameter whereby the wear is reduced to a minimum. The integral projections 26 on the tubular member 24 are adapted to fit into the openings left by punching out the integral inturned portions 23 to the effect that the tubular member 24 30 may be interlocked with the trays and, therefore, maintain its position relatively thereto under all conditions of operation. The serrated edge 25 of the tubular member 24 is forced into the relatively soft material of the knob 27 whereby these two 35 members are interlocked and a turning movement of one relatively to the other is prevented.

The members 23 fit closely on each side of 40 a nut 31, thereby causing an interlocking of these parts whereby relative motion of the nut relatively to the bolt 29, and therefore motion of the entire tray operating structure, comprising the tubular member 24, 45 knob 27, washer 28, and bolt 29, relatively to the tray 18 is prevented. The spring washer 28 compensates for whatever changes may occur in the thickness of the knob 27 in case this should shrink, after being subjected to the heat of the toaster. 50 This washer is also of value during the assembly of the device, as slight inaccuracies in the relative positions of the nut 31, bolt 29 and of the knob 27 with respect to the tubular member 24 are easily compensated 55 thereby.

Various modifications and changes may be

made herein without departing from the spirit and scope of my invention, and I desire therefore, that only such limitations 60 shall be placed thereon as are indicated in the appended claims or are imposed by the prior art.

I claim as my invention:

1. In a toaster, in combination, a frame, a tray pivotally mounted in said frame, and means for pivotally supporting and actuating said tray comprising a tubular member extending through said frame, a button operatively engaging one end of said tubular member, and means for holding said tubular member at one end only against said tray.

2. In a toaster, in combination, a frame, a tray, a tubular member interlocked with said tray and interfitted with said frame for pivotally supporting said tray therein, actuating means operatively engaging one end only of said tubular member and interlocked therewith, and means having a portion interlocked with said tray for holding said tubular member and said actuating means against said tray.

3. In a toaster, in combination, a frame, a tray having an opening of irregular contour in the side portion thereof, a tubular member having one end operatively engaging said side portion at said opening and having integral extensions located in portions of said opening and extending through said frame for pivotally supporting the tray therein, and a knob spaced from said tray by, and operatively engaging the other end of said tubular member and interlocked therewith to effect turning movements of 95 said tray.

4. In a toaster, in combination, a frame, a tray having an opening of irregular contour in the side portion thereof, a tubular member having one end operatively engaging said side portion at said opening and having integral extensions located in portions of said opening and extending through said frame for pivotally supporting the tray therein, a knob interlocked with the other end of said tubular member, a bolt extending through said knob and tubular member and a nut on said bolt operatively engaging the side portion of said tray and interlocked therewith.

In testimony whereof, I have hereunto subscribed my name this 29th day of March, 1923.

ORA A. COLBY.
